UNITED STATES PATENT OFFICE

GEORGE E. ERICSON OF MAPLEWOOD, MISSOURI, ASSIGNOR TO CARTER CARBURETOR CORPORATION, OF ST. LOUIS, MISSOURI, A CORPORATION OF DELAWARE

CARBURETOR

Application filed April 27, 1929, Serial No. 358,700. Renewed October 19, 1931.

This invention relates to carburetors for internal combustion engines and particularly to devices for maintaining a satisfactory fuel mixture ratio at all operating temperatures. This application discloses certain subject matter in common with co-pending applications Number 446,899 filed April 24, 1930 and Number 573,418 filed November 6, 1931. Carburetors of the type in which the fuel is drawn into the air stream by suction have the disadvantage that the volume of air tends to decrease relative to the volume of fuel as the temperature increases. One cause for this is that a given volume of air at high temperature contains less air by weight than the same volume at a lower temperature. Accordingly, a higher velocity at the venturi is necessary to pass a given amount of air at high temperatures than low. Another cause is that the viscosity of the fuel decreases as the temperature rises so that more fuel will flow through a jet under a given suction at high temperatures than at low. The change in volume of the fuel upon an increase of temperature is not nearly sufficient to make up for the change in viscosity. The result is that a given suction in the intake manifold will draw more fuel and less air at high temperatures than at low, resulting in lean mixtures when the motor is cold and rich mixtures when it is hot. This condition accentuates the well-known hard starting of motors when cold, due to poor vaporization, and the necessity of adjusting the carburetor so rich that fuel is wasted when the motor is hot.

It is an object of this invention to provide means for maintaining a substantially constant fuel mixture ratio at varying temperatures. It is another object of the invention to provide a carburetor having means to prevent a variation in the mixture from lean to rich as the motor heats up. Further objects will appear from the following specification and the accompanying drawing, referring to which:

Figure 1 shows a sectional side elevation of a carburetor embodying my invention.

Figure 2 shows an elevation of one form of thermally operated control means.

Figure 3 is another view of the thermal control means shown in Figure 1 with the parts in a different position.

The reference numeral 1 indicates the main body member of a carburetor having an air chamber 2 and an air inlet 3. The carburetor is attached to the engine by means of a member 4 having a suitable flange 5 for that purpose. The main body member has a circular opening 6 which receives an annular extension 7 of the body member 4. A flange 8 and screws 9 serve as means to attach the member 4 to the main body member. Dowel pins 10 may also be provided, if desired.

The member 4 has a passageway therethrough comprising an inwardly and upwardly tapering portion 11 extending from the lower part of the skirt 6 to form the throat 12 of the venturi. From the throat, the passageway extends upwardly and outwardly, forming a mixing chamber 13, and terminates in a cylindrical portion 14 extending through the flange 5. A throttle valve 15 on a shaft 16 serves to control the passage of mixture from the carburetor.

The main body member has an annular surface 17 to receive the upper edge of the fuel bowl 18. The lower part of the body member 1 is formed as an extension 19 and provided with a screw threaded bore 20, as shown. A nut 21 is screwed into the lower end of the threaded bore 20 and serves to retain the fuel bowl. A passageway 22 is formed in the extension 19 and connects the air chamber 2 with the threaded bore 20. A stand pipe 23 comprising a primary mixing chamber is attached to the main body member at the lower part of the chamber 2 by suitable screw threads 24. An opening 25 connects the upper part of the passageway 22 with the air chamber. An annular member 26 is fitted into the lower end of the stand pipe 23. Just above the annular member 26, a port 27 is formed in the wall of the stand pipe, and a primary venturi or a restricted portion 28 is formed in the bore of the stand pipe just above the port 27. A frusto-conical choke member 29 is slidably mounted on the stand pipe, and a yoke 30 mounted on a manually operable shaft 31 is provided for moving the choke into the

75

80

100

throat of the main venturi 12 when desired.

A main jet member 31a is threaded into the upper portion of the bore 20 and extends upwardly through the passageway 22 and the annular member 26 to a point near the throat of the primary venturi 28. The walls of the main jet are somewhat smaller than the inner bore of the annular member 26, as shown. Suitable bleed ports 32 may be drilled in the walls of the main jet 31 wherever desired.

An upwardly extending bore 33 is formed in the flanged member 4 and terminates in a transverse bore 34 at an edge of the throttle 15. An adjusting screw 35 having an air bleed port 36 is threaded into the bore 34, as shown. A spring 37 may be provided to frictionally maintain adjustment of the screw 35. A small tube 38 having a restricted portion 39 and an air bleed port 40 is fitted into the lower end of the bore 33. The lower end of the tube 38 is fitted into a bore 41 and the extension 19. The lower end of the bore 41 is enlarged at 42 to provide an annular recess around the end of the conduit 38, and a small port 43 is formed in the wall of the tube to communicate with the annular recess. The lower end of the bore 42 is closed by a screw 44. A transverse bore 45 is formed in the extension 19 and communicates with both the annular recess 42 and the passageway 22. The outer end of the bore 45 is closed by a plug 46. A threaded bore 47 is formed in the extension 19 to receive a jet 48 having a calibrated passage 49 therethrough. The passage 49 provides the sole communication between the fuel bowl and the bore 20.

A thermostatic baffle member 50 is supported in proximity to the inlet end of the bore 49 by a member 51 which is provided with an eye to receive the threaded portion of the jet 48 and which is held firmly against the side of the extension 19 thereby. The thermostatic member 50 comprises a pair of flat strips of metals having different coefficients of expansion, the strip of metal on the side next to the member 51 having a low coefficient of expansion, and the other strip having a high coefficient of expansion. These strips of metal are firmly attached to each other and operate in a well-known manner to bend toward the jet as the temperature increases or away from it as the temperature decreases. The thermostat is attached to the member 51 by a rivet 52 and is pivoted on the rivet so that it may be turned to one side, as shown in Figure 2, for the purpose of regulating the part of the jet which is controlled thermostatically, and also for the purpose of permitting ready access to the hexagonal head of the screw threaded jet.

The lower end of the thermostat 50 is provided with a port or perforation 59 of smaller diameter than that of the bore 49. The size of the port 59 is so calibrated that

c3 when the temperature of maximum efficiency

is reached and the member 50 contacts with the head of the jet 48, a sufficient quantity of fuel will flow through the port to supply the needs of the motor, and a further heating up of the motor will cause no further reduction in the fuel supply.

70

It will be noted upon reference to the drawing that a substantial area of the member 50 is closely adjacent and parallel to the end of the jet member 48. When the member 50 is in contact with the end of jet 48, the space between these members forms a fuel passageway through which fuel may flow at a fairly high speed.

75

According to the well-known laws of hydrodynamics, when the velocity of a fluid in motion is increased, its pressure is correspondingly decreased, so that a substantial suction is produced between the parallel adjacent areas of the members 48 and 50, such suction tending to move the member 50 into contact with the member 48, thereby closing the additional fuel inlet in advance of the time when it would normally have been closed by the temperature alone.

80

It should be noted that the lowering of pressure between the parallel surfaces of the members 50 and 48 is not entirely a result of the transmission of suction from the interior of the passageway 49. The flow is of course originally induced by suction transmitted through the passageway 49, but the resulting suction between parallel surfaces of the members 48 and 50 is actually greater than the suction per unit area in conduit 49. This may seem unreasonable at first thought, but the truth of the proposition may be clearly illustrated as follows:

85

Reverse the flow of fluid through the passage 49 by producing a pressure instead of a suction in the mixing conduit. There will be a resulting flow of fluid between the parallel surfaces of the members 48 and 50, but, of course, in an opposite direction. The member 50 will now be drawn toward the member 48 by the suction existing between the parallel surfaces due to the fact that a fluid is flowing therebetween. The pressure which initiates the flow would normally be expected to push the member 50 away from the member 48, and since this does not occur, it is obvious that there is another force of greater magnitude than the pressure itself which may be readily illustrated by the well-known fact that it is difficult to blow a disk 110 of paper off the end of a spool.

105

It will be understood that the only times at which the suction becomes great enough to move the member 50 a substantial distance are when the engine is operating at nearly full speed and power, or when the choke 29 is closed so that the suction is concentrated on the parallel areas between the members 48 and 50.

115

The minimum fuel supply may be regu- 130

lated by turning the member 50 on the pivot, so that less than the full diameter of the port 59 will register with the bore 49. When desired, the member 50 may be adjusted so that the port 59 goes out of registration altogether, and the side of the member 50 regulated to uncover more or less of the bore 49 as desired.

It will be understood that the thermostat 10 may be used without the port 59 and regulated so as never to entirely close the bore 49.

It will be understood that the main jet member 31a is provided with suitable calibrated passageways 53 leading from the bore 15 20 to the main bore of the jet and to the passageway 22.

Suitable conventional means is provided for supplying fuel to the bowl 18 in which it is maintained at a substantial constant level 20 by the float 54. The fuel supply conduit and inlet valve being entirely conventional and forming no part of this invention are not shown.

The operation of the device is as follows: 25 The carburetor being attached to an internal combustion engine, suction in the passageway 14 is produced by operation of the engine. With the valve substantially at closed position, as shown, fuel is drawn up 30 from the fuel bowl 18 through the passageways 49, 53, 46, 38, 33, and 34 into the passageway 14 above the throttle. Air is bled in at the port 40 and also at that portion of the bore 34 below the edge of the throttle. A 35 comparatively small amount of mixture entering in this manner serves to operate the engine at idling speeds. It will be noted that suction is transmitted from the outlet side of the throttle through the port 34 and 40 through passages 33, et cetera, to passage 49, and to the member 50, so that whether the throttle is in opened or partially open position, as for a proper idle adjustment, suction may be transferred to the member 50. This 45 will have more effect, of course, when the valve 29 is in closed position, as for starting at low temperature. It is highly desirable that this suction from above the throttle be available for operating the valve 50; otherwise, with the valve 29 in closed position, too 50 rich a mixture would be delivered after the engine starts to run under its own power and after the suction has been increased in that manner.

55 The change in the suction developed by the engine when it starts to run under its own power is due to the fact that its speed increases. The normal cranking speeds of an internal combustion engine are usually from 40 to 100 R. P. M., while the normal idle speeds of the same engines are from 200 to 400 R. P. M., so that when an engine starts to run under its own power, there is an instant increase in the suction. This makes it 65 necessary to supply a leaner mixture just

after starting than during cranking speeds. In fact, there are several reasons for supplying a leaner mixture after the engine starts to run under its own power, but one of the most important is that the increase of suction causes the fuel to vaporize more readily, so that some vaporized fuel and less raw fuel is delivered. The connection from above the throttle to the thermo-suction valve 50 provides means for automatically switching the mixture ratio from rich to lean as soon as the engine starts to run under its own power (assuming the choke valve 29 is in closed position for low temperature starting).

For high temperature starting, the valve 29 is not fully closed or not closed at all, and the suction from above the throttle is relieved to quite a substantial extent due to the fact that the nozzle 27 is exposed to atmospheric pressure, and, under these conditions, the valve 50 would not be moved to closed position unless it has already been moved to that position by the temperature.

When the throttle 15 is opened, air is drawn through the inlet 3, the air chamber 2, the throat of the venturi 12, and the mixing chamber 13. A smaller quantity of air passes from the chamber 2 through the port 27, the primary venturi 28, and the stand pipe into the mixing chamber. When the engine is running at high speeds with the throttle valve nearly or full open, air also passes down through the bore 25 into the passageway 22 and bleeds into the ports 32 in the wall of the main jet. The suction at the main and primary venturis draws fuel through the bores 49, 20, and 53, the amount of fuel drawn in by a given suction being calibrated by the resistance to flow presented by these bores. When the engine is being started cold, it is desirable to temporarily increase the ratio of fuel to air, and for this purpose the choke valve 29 is moved into the throat 12 of the venturi to partially or fully close the same, as desired. By this means, all the suction in the intake manifold is transmitted to the venturi 28 and the idling tube, causing a strong suction on this and a resulting increase in the flow of fuel. This strong suction being applied to the member 50 at the end of the jet 48 will cause said member to be drawn to closed position and thereby restrict the flow of fuel into the mixing conduit. This is desirable, because the highly restricted passageway around the standpipe 23 causes the suction to be increased to such a point that sufficient fuel will be drawn in even through the restricted orifice 59. In fact, this partial closing of the fuel inlet permits the use of a more highly restricted air inlet and also higher suctions at cranking speeds, and the increased suction of itself results in better vaporization of the gasoline.

If the passageway 49 should be left open and unrestricted during the choking action of

the valve 29, then the restricting effect of that valve can not be carried as far as if the fuel inlet 49 were restricted; otherwise, so much raw fuel would be drawn into the engine that it would be flooded at the first fire.

Under the above conditions, the low temperature bends the thermostat 50 away from the end of the jet 48, and the resistance of the bore 49 is at a minimum. After the engine has been started and warmed up, it is no longer desirable to have an increased fuel supply relative to the amount of air being used, and the choke valve 28 is opened.

As the temperature increases, resulting in an increase in the amount of suction required at the venturi to draw in a given volume of air, the effect of the increased suction on the jet 48 is obviated by the movement of the thermostatic baffle member 50 toward the end of the jet under the influence of the increased temperature.

It will be understood that the member 50 can be adjusted so that it will cover any desired portion of the end of the bore 49 or so that the port 59 will be full or partly in registration with the end of the bore 49. The member 51 is shown as a single piece of metal furnishing a rigid support for the thermostat. It will be understood, however, that this member could also be formed in the same way as the member 50 with the metal so arranged as to have an effect cumulative to that of the thermostat 50. Ordinarily, the space between the inside of thermostat 50 and the head of the jet 48 at low temperatures is approximately one-third of the diameter of the bore 49. This space is shown somewhat exaggerated for clearness of illustration.

It will be understood that, under special conditions, such as starting, no attempt is made to maintain an exactly constant fuel ratio, because the desirability of excess fuel under these conditions is well known. Also, when the motor is heated to extreme temperatures, a very lean mixture, although quite efficient, is undesired, because it tends to further heat the motor, because the combustion of a weak mixture occurs at a comparatively slow rate, causing the combustion chamber, piston head, and the upper portion of the cylinder walls to be exposed to the flame for longer periods. The heating effect is increased by the exposure of a greater part of the cylinder walls to the flame on account of the fact that the slower burning mixture continues to burn as the piston recedes, and the flame comes in contact with the cylinder walls as they are uncovered by the piston; whereas, with a proper mixture the combustion would be near completion before any substantial portion of the cylinder walls had been uncovered.

It will be seen that this device, when properly adjusted, is capable of maintaining a

substantial, constant fuel-air ratio under normal operating conditions, and that the abnormal conditions at low temperatures are taken care of by the manually operated choke, while, beyond a predetermined temperature limit, an increase of the fuel to air ratio is permitted due to the fact that a part of the opening 49 is never closed, permitting the increased suction to draw greater quantities of the thin, hot fuel through the carburetor. As above explained, the increased suction is due to the fact that the increased volume of the air at these temperatures makes it necessary to open the throttle wider to permit a given volume of air to be drawn into the engine, thus increasing the suction on the jet on account of the higher velocity through the venturi.

It will be understood that, while no connection from the inlet 3 to an exhaust stove is shown, I contemplate using this carburetor on the usual type of automobile engine and mounting it under the hood in the usual manner. As automobile engines also have an exhaust pipe exposed to the atmosphere under the hood, it will be seen that the air will be heated by the exhaust manifold upon operation of the engine, no matter whether the air comes directly from the air stove or not.

It will be understood that the invention is susceptible of many modifications, and, accordingly, I do not wish to be limited in my protection, except as set forth in the accompanying claims.

I claim:

1. In a carburetor, a fuel chamber, a main supply jet, a calibrated passageway providing communication between the fuel chamber and said main jet, a perforated thermostatic plate mounted adjacent the entrance of said passageway, said perforation forming a metering orifice being of smaller diameter than said passageway, and means to move the perforated portion of said plate toward and away from said passageway.

2. In a carburetor, a fuel chamber, a fuel jet adapted to be supplied with fuel from said chamber, a discharge port leading from said fuel chamber toward said jet, a movable plate mounted in said fuel chamber adjacent said discharge port, a perforation in said plate of smaller diameter than said port, and heat controlled means for adjusting the position of said plate with respect to said port.

3. In a carburetor, a mixing conduit for fuel and air, a source of fuel supply, a calibrated passageway leading from said source of supply toward said conduit, a member mounted adjacent one end of said passageway having a perforation therein of less diameter than said passageway, such device being constructed and arranged to permit the flow of fuel through the perforation or alternatively around the member and heat

controlled means for moving said member toward or away from said passageway.

4. In a carburetor, means forming a mixing conduit, a fuel conduit for delivering fuel to said mixing conduit, said mixing conduit having an air inlet and said fuel conduit having a fuel inlet, valve means for controlling one of said inlets, a portion of said valve being cut away to establish a predetermined minimum passageway when the valve is in closed position, and means for controlling said valve by heat and suction to vary the mixture of air and fuel from rich to lean as the temperature and suction increase.
5. In a carburetor, means forming a mixing conduit, a fuel conduit for delivering fuel to said mixing conduit, said mixing conduit having an air inlet and said fuel conduit having a fuel inlet, valve means for controlling one of said inlets, a portion of said valve being cut away to establish a predetermined minimum passageway when the valve is in closed position, means for operating said valve by heat and suction to vary the mixture of air and fuel from lean to rich, and vice versa, a throttle valve in said mixing conduit for controlling the discharge of mixture therefrom, and a suction connection leading from a point in said mixing conduit posterior to said throttle and adapted to apply suction to said valve for operating it to lean out the mixture.
6. In a plain tube carburetor, means forming a mixing conduit, means for admitting air to said mixing conduit comprising an air inlet, means for admitting fuel to said mixing conduit comprising a fuel inlet, a valve in one of said inlets, means for causing said valve to respond to either suction or temperature changes and thereby lean out the mixture upon an increase of suction or temperature or both, and to enrich the mixture upon a decrease of suction or temperature or both, and a perforation in said valve to provide a predetermined minimum restriction to said inlet.
7. In a plain tube carburetor, means forming a mixing conduit, means for admitting air to said mixing conduit comprising an air inlet, means for admitting fuel to said mixing conduit comprising a fuel inlet, a valve in one of said inlets, means for causing said valve to respond to either suction or temperature changes and thereby lean out the mixture upon an increase of suction or temperature or both, and to enrich the mixture upon a decrease of suction or temperature or both, a suction connection leading from a point in said mixing conduit posterior to said throttle for operating said valve, and a perforation in said valve to provide a predetermined minimum restriction to said inlet.

In testimony whereof I affix my signature.
GEORGE R. ERICSON.
